(57) **CLAIM**

The ornamental design for a camera support, as shown and described.

DESCRIPTION

FIG. 1 is a perspective view of a camera support showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear and right side perspective view thereof; and, FIG. 9 is a front and left side perspective view thereof.

The broken lines depict portions of the camera support in which the design is embodied that form no part of the claimed design.
